United States Patent Office

Des. 232,082

Patented July 16, 1974

232,082

DISPENSING CONTAINER

William E. Fitzpatrick, Oakland, N.J., and Timothy F. Gary, Dover, Del., assignors to Rapid-American Corporation, New York, N.Y.

Filed Apr. 24, 1972, Ser. No. 247,258

Term of patent 14 years

Int. Cl. D9—03

U.S. Cl. D9—224

FIG. 4

FIG. 6

FIG. 5

FIG. 7

FIG. 1 is a front perspective view of a dispensing container showing our new design;

FIG. 2 is a front perspective view with the lid opened;

FIG. 3 is a front elevational view with the lid opened;

FIG. 4 is an elevational view looking from the left of FIG. 3;

FIG. 5 is a top plan view thereof;

FIG. 6 is a rear elevational view thereof; and

FIG. 7 is a bottom plan view thereof.

We claim:

The ornamental design for a dispensing container, as shown and described.
